Des. 216,321
Patented Dec. 16, 1969

216,321

COMBINED WRIST WATCH AND RADIO

Frank J. Forey, 3057 Leeward Ave.,
Los Angeles, Calif. 90005

Filed Dec. 16, 1968, Ser. No. 14,970

Term of patent 14 years

Int. Cl. D10—02

U.S. Cl. D42—8

FIG. 1.

FIG. 2.

FIG. 3.

FIG. 4.

FIG. 5.

FIG. 6.

FIGURE 1 is a top plan view of a combined wrist watch and radio showing my new design;

FIGURE 2 is a bottom plan view thereof;

FIGURE 3 is a front elevational view;

FIGURE 4 is a rear elevational view;

FIGURE 5 is a right side elevational view; and

FIGURE 6 is a left side elevational view.

I claim:

The ornamental design for a combined wrist watch and radio, substantially as shown.
